UNITED STATES PATENT OFFICE.

LEO D. BENDER, OF CHICAGO, ILLINOIS.

PHOTOGRAPH-HOLDER.

1,333,531.

Specification of Letters Patent.

Patented Mar. 9, 1920.

Application filed September 23, 1918. Serial No. 255,255.

To all whom it may concern:

Be it known that I, LEO D. BENDER, a citizen of the United States, and a resident of Chicago, in the county of Cook and State 5 of Illinois, have invented certain new and useful Improvements in Photograph-Holders, of which the following is a specification.

My invention relates to photograph holders and the object is to provide an improved 10 holder for mounting, protecting and mailing a photograph and which can be opened up and its sections locked together to form a rigid and neat frame for displaying the 15 photograph.

On the accompanying drawing the construction of my device is clearly shown. On the drawing:

Figure 1 is a plan view of the unfolded 20 holder,

Fig. 2 is an end view of the unfolded holder, the dotted lines showing it partly folded,

Fig. 3 is a plan view of the partly folded 25 holder,

Fig. 4 is an end view showing the holder entirely folded, and

Fig. 5 is a top view showing the holder unfolded and the sections locked together to 30 form a display stand.

The holder comprises the sections A, B, C and D, all forming part of a single sheet of paper, the section D being a narrow flap. Against the back of the section A is secured, 35 as by pasting, the mounting board E which is of heavier and stiffer paper than the part comprising the sections A, B, C and D, and this mounting board has at its corners the paper clips or pockets *a* for receiving the 40 corners of the photograph to be mounted.

As shown in Fig. 3, and by dotted lines in Fig. 2, the section A with the mounting board E thereon is folded against the section B to display the photograph when the 45 holder lays flat. The sections B and C form

covers for the mount holding section and the flap D by engaging around the folding edge of the sections A and B lock the sections B and C together against the mount holding section so that the photograph is 50 protected and the holder held closed. In this condition the holder can readily be mailed and if desired the flap can be pasted down or stickers applied to hold it in place during mailing. 55

Fig. 5 shows the holder unfolded and the sections brought together to form the triangular display frame or stand. To hold the sections in unfolded position and form a rigid frame the flap is inserted between 60 the edges of the section A and the mounting board E thereon, these edge sections being left unglued a sufficient distance to permit entry of the flap, and these edge sections will exert sufficient pressure on the flap to hold 65 it in place so that a rigid frame is formed for displaying the photograph.

I do not desire to be limited to the exact construction shown and described as modifications are no doubt possible which would 70 still come within the scope of the invention.

I claim as follows:

A photograph holder comprising a rectangular sheet of material, divided along parallel fold lines into end sections and a central 75 section of substantially equal size, a photograph mounting board attached to one of said end sections, the other end section being provided with an end marginal flap serving to seal said holder when said sections are 80 folded upon each other and to be inserted between the corresponding margins of said photograph mounting board and the other end sections when said holder is folded to display said photograph mounting board. 85

In witness whereof, I hereunto subscribe my name this 19th day of September, A. D., 1918.

LEO D. BENDER.
